GESELLSCHAFT M. B. H., OF VIENNA, AUSTRIA-HUNGARY.

FASTENER FOR PAPER BAGS AND THE LIKE.

1,069,044.

Specification of Letters Patent.

Patented July 29, 1913.

Application filed November 20, 1911. Serial No. 661,358.

To all whom it may concern:

Be it known that I, ALADAR TRAUB, a subject of the Emperor of Austria-Hungary, residing at Vienna, Austria-Hungary, have ⁵ invented new and useful Improvements in Fasteners for Paper Bags and the Like, of which the following is a specification.

The present invention relates to a fastener for holding loose sheets of paper and the ¹⁰ like parallel to the edge seized or to the folded edge seized, which fastener is particularly adapted for securing the closure of paper bags, and will form a reliable link for fitting a carrier, for instance for carrying the thus closed paper bag, or may be ¹⁵ made to serve itself as a carrier.

The accompanying drawings illustrate several constructional forms of the invention and the manner it is employed.

²⁰ Figure 1 illustrates one form of the device. Fig. 2 illustrates a second form. Fig. 2^a illustrates a third form. Fig. 3 illustrates a fourth form. Figs. 4 to 12 inclusive illustrate diagrammatically the manner of applying the fastener to the paper. Fig. 13 illustrates a perspective view of a fifth form of the device.

In the constructional form according to Fig. 1 the fastener consists of a piece of ³⁰ sheet metal drawn in form of a J, the longer leg 1 of which has its sides inwardly tapered to form two notches 2 in its sides, so that it can be easily folded over the short leg 3. The edge of the short leg is slightly hollowed out, so that points 4 are produced at ³⁵ the corners, which points will enter into the paper and thereby facilitate the secure hold of the fastener. For the same purpose the edge is besides preferably provided with ⁴⁰ prongs or the like. This may also be the case with the edge of the long leg 1.

Fig. 2 illustrates another modification, in ⁴⁵ which the bending over is facilitated by the sheet metal being perforated at the place where it is to be bent over. Both the edge of the long and that of the short leg are serrated. The serrations and the edge of the short leg are so arranged, that when the fastener is bent over, these serrations will penetrate through the paper into holes provided in the metal. The grip of the fastener on the paper is thereby greatly increased. In ⁵⁰ place of the long leg having notches at the sides according to Fig. 1, or a row of holes at the bending line according to Fig. 2 the

bending may be facilitated by the whole fastener being made of thin sheet metal, and the latter being reinforced by indents or the like at those parts where it is subject to high strains, that is particularly at the joint between the short and the long leg. Such a constructional form is shown in Fig. 2^a. Here the short leg and the lower part of the long leg are provided up to the bending line with corrugations, which extend beyond the ⁶⁰ joint between the two legs. The corrugations are impressed either during or after the bending into shape of the two legs, preferably by the suitably shaped die, which produces the bend, impressing the corrugations into the bent bend with a last pressure. These corrugations need, of course, not extend as far as the edge of the legs. ⁶⁵

Fig. 3 is a constructional form, according to which the fastener consists of a wire ⁷⁰ frame likewise bent into the shape of a J.

Paper bags and the like are closed by means of the hereinbefore described fasteners in the following manner: The edges of the mouth of the bag are laid together and ⁸⁰ introduced between the legs of the fastener (Fig. 4.) Now the edges of the paper are folded over the edge of the short leg. This can be done in an easy and quick manner by the fastener being turned in the direction of ⁸⁵ the arrow, Fig. 4, until it has the position in Fig. 5. Then the long leg is bent over the short one in the direction of the arrow in Fig. 5, whereby the closure is completed, ⁹⁰ Fig. 6. If a carrier is to be combined with the fastener, a carrier ring 6 may be inserted as shown in Fig. 6. In place of this ring of course also a loop or the like may be employed. The weight of the parcel will produce so great a friction between the paper and the edge 7 of the short leg, that the ⁹⁵ edge of the bag will be securely held between the legs, which will be further assisted by the action of the points 4. The component P, Fig. 6, of the weight of the parcel will also produce a friction at the edges 8 and 9 of the bent over fastener, so that there will be no fear of the edges of the paper slipping out of the fastener.

It will be of advantage to first fold over ¹⁰⁰ the edge of the bag before the fastener is fitted, as this will increase the friction and strengthen the closure. The Figs. 7, 8 and 9 illustrate the operations in making the closure. It will be still better to fold over ¹¹⁰

the edge of the bag in the manner shown in Fig. 10, where the supporting parts of the bag are in the finished closure prevented by the double paper from tearing at the 5 sharp edge 10, Figs. 11 and 12.

In the modes of use in Figs. 7 to 12 the fastener is applied not to the edge of the paper bags to be closed but to their common fold.

- 10 In the constructional form shown in Fig. 13 the fastener is formed so as to serve at the same time as a carrier for the paper bag closed with the fastener. The fastener is in this case preferably stamped of an endless 15 band of sheet metal so that the edges 1 and 13, at which the piece of metal is cut off from the whole band are of a congruent curvature, so that the several pieces are stamped out of the whole without any waste.
- 20 The piece of metal is then bent in the J-shape the same as with the hereinbefore described constructional forms. The portion 14 has a cut 11 made in it by means of which cut there is formed a long leg portion 12 25 which may be bent over a short leg 13 in the manner hereinbefore described. The remaining or marginal part of the portion 14 which is not bent over will form a sort of loop or carrier, by which the sheets of paper, 30 the bag or the like, to which the fastener has been fitted, may be conveniently carried. The edges of the cut 11 are preferably beaded over, so as to remove the sharp edge 35 which would be inconveniently felt in carrying the parcel.

The essential feature common to all the hereinbefore described constructional forms consists in that the papers to be united or carried are gripped by a fold made over a sharp edge and held by the friction produced thereby. This is above all obtained by means of the short leg of the fastener, against the upper edge of which the paper is drawn the tighter, the greater the load. 40 The bending over of the upper tongue is of less importance for obtaining this effect; the tongue serves chiefly for the attachment of

the carrier and is indeed of great importance in consequence of the simple and safe manner of the attachment enabled thereby. 50

Claims:

1. A combined fastener and carrier for paper bags and the like, consisting of a flat piece of metal bent into the shape of a J to form a pocket adapted to receive the 55 edges of the mouth of a paper bag, a part of the long leg thereof being adapted to be bent over the paper to clamp the same between said part of the long leg and the short leg, the sides of said part being inwardly 60 tapered at the bending line, the edge of the short leg of said piece of metal opposite to the bending line having a concave curvature and terminating in points.

2. A combined fastener and carrier for 65 paper bags and the like consisting of a piece of sheet metal bent in the shape of a J to form a pocket, the long portion of said piece of sheet metal having a U-shaped incision forming a portion adapted to be 70 bent over the edge of the paper to be introduced into the pocket formed by said piece of sheet metal, the remaining part of said long portion forming a carrier.

3. A combined fastener and carrier for 75 paper bags and the like consisting of a piece of sheet metal bent in the shape of a J to form a pocket, the long portion of said piece of sheet metal having a U-shaped incision forming a portion, adapted to be bent 80 over the edge of the paper to be introduced into the pocket formed by said piece of sheet metal, the remaining part of said long portion forming a carrier, the upper edge of the short leg of said piece of sheet metal having 85 a concave curvature and terminating at the corners in points.

In testimony whereof I have signed my name to this specification in the presence of two subscribing witnesses.

ALADAR TRAUB.
